Inventor

Donald S. Barrows

By *Frank J. McLean*
his Attorney

UNITED STATES PATENT OFFICE.

DONALD S. BARROWS, OF ROCHESTER, NEW YORK, ASSIGNOR TO THE SYMINGTON COMPANY, OF NEW YORK, N. Y., A CORPORATION OF MARYLAND.

DRAFT RIGGING.

Application filed January 30, 1925. Serial No. 5,762.

My invention relates to draft rigging for railway cars and more particularly to mechanism for operatively connecting the coupler to the yoke member and permitting a desired amount of angling motion therebetween.

The principal feature of the invention, generally stated, is the provision of means for connecting a coupler to a yoke so that a desired amount of horizontal angling is permitted together with a small amount of upright or substantially vertical rocking motion therebetween.

An object of the invention is the provision of a connection between the coupler and yoke members in railway draft rigging in which the rear face of the butt portion of the coupler is crowned or curved so that it can rock or roll vertically on the front of the follower block, an interposed member or a transverse bridge integral with the yoke.

Another object of the invention is the provision of an improved connection between the coupler and the yoke member of railway draft rigging whereby substantially universal motion is permitted therebetween, said object being accomplished by pivoting a butt portion or swivel block to the stem of the coupler and crowning or curving the rear face of said block so that it will roll or rock, at an angle to the plane of motion permitted between the coupler stem and swivel block, on a portion of the yoke.

A further object of the invention is the provision of an improved swivel connection between a coupler and yoke for railway draft rigging in which an intermediate swivel member is provided between the coupler stem and a preferably integral bridge or diaphragm portion on the yoke, said intermediate member being connected to the coupler stem for pivotal motion in one plane and being formed for rocking motion with respect to the yoke in another plane at an angle thereto.

A still further object of the invention is the provision of an improved and simplified form of universal connection between the coupler and yoke, in which the draft forces placed upon said yoke by the coupler are first transmitted to a member adapted to pivotally connect, for horizontal swinging movement, said coupler and an intermediate swivel block, and are then transmitted

from said swivel block to the yoke through a connecting key, the swivel block member also being adapted to have an upright rocking engagement upon a portion of the yoke.

The invention further consists in the construction of the several elements and their particular arrangement and combination as hereinafter set forth.

In the drawings illustrating my invention, the scope whereof is defined by the appended claims:

Figure 1 is a top plan view partly in horizontal section illustrating a coupler and a yoke member constructed and connected in accordance with my invention.

Figure 2 is a vertical longitudinal section on the line 2—2 of Figure 1.

Referring to the drawings in which similar reference characters designate corresponding parts, I have shown the coupler 1 connected to a butt portion or swivel block 2 by means of a pivot pin 3, which permits substantially horizontal angling movement therebetween. The swivel block or butt portion 2 is connected to the yoke 4 by the transversely extending key 5 which passes through a slot 6 of the swivel block and slots or apertures 7 and 8 in forwardly extending walls or webs 9 and 11 of the yoke 4. The coupler could, of course, be described as being formed of a plurality of interleaved members having a pivotal connection therebetween.

As will be apparent from an inspection of Figure 2, the pivot pin 3 is divided into two portions 12 and 13 by the transversely extending key 5, the upper portion 12 being supported on said key when assembled and the lower portion 13 being supported on a flange 14 of the swivel block, which flange is preferably integral with said swivel block and supports the bottom of the key section 13 substantially flush with the lower face of the main portion of said block.

The coupler 1 or stem portion thereof is provided with rearwardly extending flanges 15 and 16, said flanges being perforated at 17 and 18 respectively for the reception of the respective portions of the pivot pin and the rearward edges of said flanges are curved co-axially with respect to said perforations at 19 and 21, respectively. The flanges 15 and 16 of the coupler closely fit in the pockets 22 and 23 provided in the swivel block

or butt portion 2. The bottom or rearward face of each pocket is curved co-axially with respect to the pivot apertures so that the flanges 15 and 16 on the coupler are adapted 5 to fit into said pockets with the co-axial portions of the pockets for transmitting buffing forces therebetween.

The swivel block or butt portion 2 is provided with upper and lower flanges 24 and 10 25, respectively, and an intermediate flange portion 26 which is intersected, as shown, by the key member 5. The rearward face 27 of the swivel block 2 is crowned or curved, as shown, so as to rock or roll in an upright 15 or substantially vertical direction upon the transverse member 28. This member 28 may conveniently be formed as a transverse bridge of the yoke which, in the present embodiment, is shown as of the vertical 20 type. The front face of the portion 28, which in the present embodiment is shown as integral with the yoke, is illustrated as being convexly curved or crowned but, if desired, the same may be flat or concavely 25 curved provided the radius of curvature is substantially greater than that of the cooperating face 27 on the swivel block or butt portion 2. It is obvious, however, that the shapes of the engaging faces at this point 30 are interchangeable, it merely being necessary to allow rocking movement therebetween. The rear face of the bridge portion 28 is adapted for engagement with cushioning mechanism represented diagrammatically by the dotted lines adjacent thereto.

The forwardly extending arms of the yoke member are shown at 29 and 31 and it is to be understood that the rear or U-shaped portion of the yoke may be of any ordinary 40 or desired construction. Forwardly of the integral bridge portion 28 the arms 29 and 31 are joined by flange or web portions 9 and 11 forming a yoke of the hooded type. These flange portions 9 and 11 are those portions of the yoke through which the key 5 extends, as previously mentioned. For supporting the key the same extends through slots 34 in the draft sills 35 and through corresponding slots 36 in the cheek plates 37.

50 By means of the aforesaid construction a coupler and yoke connection has been provided in which a desired amount of horizontal angling is permitted between the coupler and its associated swivel block or butt portion, whereas undue angling or pivoting between the coupler and yoke is prevented by the forwardly extending portions 9 and 11 of the yoke. Likewise, a desired amount of vertical rocking is permitted between the 55 swivel portion 2 and the yoke 4 by the engagement of the crowned face 27 of the swivel block and the transverse web or diaphragm portion 28 on the yoke. This rocking motion is limited by the portions of the 60 forwardly extending arms 29 and 31 in front

of or beyond the transverse portion 28. It will be noted that these portions, together with the flanges or webs 9 and 11, form a pocket or box-like structure into which the coupler and its associated swivel block or 70 butt portion are inserted.

When in assembled position, as shown in Figure 2, it will be seen that the pin, or the upper portion thereof, is prevented from being removed by the overlapping edge of 75 the arm 29 of the yoke. The edge of the lower arm 31 of the yoke likewise serves as additional means for preventing loss of the lower portion of the pivot pin.

On the application of draft force to the 80 coupler such force is transmitted from the coupler stem, first, through the pivot pin or pins to the swivel block or butt portion 2, then to the key 5, and then to the yoke 4, as will be understood. Upon the application 85 of buffing force to the coupler, however, the key 5 and pivot pin 3 are relieved by the direct engagement between the rear of the coupler stem and the cooperating pockets in the swivel block and the crowned rear face 90 of said swivel block with the transverse integral portion on the yoke.

Having now described my invention, what I claim as new and desire to secure by Letters Patent, is:

1. In a railway draft rigging, the combination with a yoke having a transverse web portion connecting the forward ends thereof, of a coupler stem, and a crowned portion on the rear end thereof adapted to engage the 10 web portion of the yoke and rock up and down thereon to a limited extent.

2. In a railway draft rigging, the combination with a yoke having a transverse web portion connecting forward ends thereof, a 10 coupler stem comprising a plurality of relatively rotatable members, cooperating bearing portions provided on said members adapted to transmit buffing forces from one to the other, and a crowned portion on the 11 rear end of the coupler stem adapted to engage the web portion of the yoke and rock thereon.

3. In a railway draft rigging, the combination with a yoke having a transverse 11 member integrally connecting the arms thereof, of a coupler adapted to engage said member and one of the engaging surfaces curved convexly so as to permit a limited up and down rocking movement therebetween.

4. In a railway draft rigging, the combination with a yoke having a cushioning mechanism pocket and a coupler pocket, of a two-part coupler extending into the coupler pocket, one of said parts being pivoted 11 to swing horizontally and both adapted to rock vertically.

5. In a railway draft rigging, the combination with a yoke having pockets on opposite sides of a transverse bridge portion, of

- a coupler stem extending into one of said pockets, the rearward end of said stem being crowned for upright rocking engagement with said bridge portion.
- 5 6. In a railway draft rigging, the combination with a yoke, of an integral transverse bridge portion thereon, a cushioning mechanism pocket provided on one side of said bridge portion, a coupler pocket provided on the other side thereof, and a crowned coupler stem extending into said pocket and engaging the bridge portion for vertical rocking movement thereon.
- 10 7. In a railway draft rigging, the combination with a yoke, of an integral transverse bridge portion thereon, a cushioning mechanism pocket provided on one side of said bridge portion, a coupler pocket on the other side thereof, a crowned coupler stem extending into said pocket and engaging the bridge portion for up and down rocking movement thereon, and means uniting said yoke and coupler for transmitting draft forces therebetween.
- 15 8. In a railway draft rigging, the combination with a yoke, of an integral transverse bridge portion thereon, a cushioning mechanism pocket provided on one side of said bridge portion, a coupler pocket on the other side thereof, a crowned coupler stem extending into said coupler pocket and engaging the bridge portion for upright rocking movement thereon, said stem being articulated for angling movement between portions thereof.
- 20 9. In a railway draft rigging, the combination with a yoke, of an integral transverse bridge portion thereon, a pocket provided on each side of said bridge portion, the front side of said bridge portion being crowned, and a crowned coupler stem extending to and engaging said crowned bridge portion for upright rocking movement thereon.
- 25 10. In a railway draft rigging having cushioning mechanism, the combination with a yoke having forwardly extending arms, of a member between said arms engaged by the cushioning mechanism on one side thereof, and a crowned coupler stem engaging the other side of said member and adapted to rock vertically thereon.
- 30 11. In a railway draft rigging having cushioning mechanism, the combination with a yoke having forwardly extending arms, of a member between said arms having one side engaged by the cushioning mechanism, and a crowned coupler stem engaging the other side thereof and adapted for upright rocking thereon, said stem being articulated for horizontal angling between portions thereof.
- 35 12. In a railway draft rigging, the combination with a yoke, of a coupler stem, and a crowned butt portion swiveled to said stem and engaging a portion of the yoke for rocking movement thereon.
- 40 13. In a railway draft rigging, the combination with a yoke, of a coupler stem, and a crowned butt portion swiveled for horizontal angling of the stem with respect thereto and engaging a portion of the yoke for upright rocking movement thereon. 70
- 45 14. In a railway draft rigging, the combination with a yoke, of a transverse wall portion thereon, cushioning mechanism engaging one side of said wall portion, a coupler butt portion engaging the other side thereof and adapted to rock thereon in one plane, and a coupler stem pivoted to said butt portion for rocking in a plane at an angle to the first plane. 75
- 50 15. In a railway draft rigging, the combination with a yoke, of a coupler, a butt portion connected thereto by pivotal means adapted to transmit draft forces therebetween, and a key member extending at an angle to the pivotal means for transmitting draft forces between the butt portion and the yoke, said butt portion abutting a portion of the yoke for the transmission of buffing forces. 80 85
- 55 16. In a railway draft rigging, the combination with a yoke, of a coupler, a butt portion, a pivot pin connecting said coupler to said butt portion, and a flange on the lower portion of said butt portion for supporting said pivot pin. 90
- 60 17. In a railway draft rigging, the combination with a yoke, of a coupler, a swivel block, a pivot pin connecting said coupler and swivel block, a key intersecting said coupler and swivel block, cutting the pivot pin into two sections and supporting the top section thereof. 100 105
- 65 18. In a railway draft rigging, the combination with a yoke, of a coupler, a swivel block, a pivot pin connecting said coupler and swivel block, a key cutting said pin into two sections, supporting the top and serving to connect the swivel block with the yoke, and a flange on the swivel block for supporting the bottom section. 110
- 70 19. A coupler comprising a stem portion provided with rearwardly extending flanges perforated for a pivot pin and provided with edges curved co-axially with respect to said perforations, a butt portion for said coupler crowned for rocking engagement with the adjacent member of associated draft rigging, provided with spaced complementary flanges overlapping the flanges on the stem and similarly perforated, and provided with pockets coaxially curved with respect to the perforations and engaging the curved flanges of the stem portion for transmitting buffing forces therebetween, and a pin extending through the perforations for pivoting the stem and butt portions together and transmitting draft forces therebetween. 115 120 125
- 75 86 130

20. A coupler comprising a stem portion provided with rearwardly extending flanges perforated and provided with edge portions curved co-axially with respect to said perforations, a butt portion provided with alternately spaced complementary flanges overlapping the flanges on the stem portion, similarly perforated and provided with pockets co-axially curved with respect to the perforations and engaging the curved flanges of the stem portion for transmitting buffing forces therebetween, and a pivot pin extending through the perforations for connecting the butt and stem portions together and transmitting draft forces therebetween, said butt portion being slotted for the reception of a key for connecting the coupler and yoke and crowned for rocking engagement therewith.
- 20 21. A yoke provided with an integral transverse bridge portion for engagement with cushioning mechanism on one side and crowned for vertical rocking engagement with a coupler member on the other side, the arms of said yoke being extended beyond
- 5 said crowned side and adapted to limit said rocking.
22. A yoke provided with an integral bridge portion for engagement with cushioning mechanism on one side and curved 30 for vertical rocking engagement with a coupler member on the other side, said yoke also being provided with forwardly extending slotted portions for the reception of a key and forming a pocket to receive the 35 butt of an associated coupler.
23. In railway draft rigging in combination with a yoke having forwardly extending arms, a member disposed between said arms and normally engaged by the cushioning mechanism on one side thereof, a coupler stem with a curved butt portion engaging the other side of said member for angling with respect thereto, and a horizontal key intersecting said stem and yoke for transmitting draft forces therebetween. 40 45

In testimony whereof I affix my signature.

DONALD S. BARROWS.
